CLAIM

The ornamental design for a nail clipper, as shown and described.

DESCRIPTION

FIG. 1 is a front elevation view of the nail clipper of the present design, the rear elevation view being a mirror image thereof;

FIG. 2 is a top plan view thereof;

FIG. 3 is a bottom plan view thereof;

FIG. 4 is a right side elevation view thereof;

FIG. 5 is a left side elevation view thereof;

FIG. 6 is a bottom plan view of the lever;

FIG. 7 is a top plan view with the lever removed;

FIG. 8 is a section view thereof taken along 8-8 lines of FIG. 1;

FIG. 9 is a section view thereof taken along 9-9 lines of FIG. 1;

FIG. 10 is a section view thereof taken along 10-10 lines of FIG. 1;

FIG. 11 is a section view thereof taken along 11-11 lines of FIG. 1;

FIG. 12 is a section view thereof taken along 12-12 lines of FIG. 2;

FIG. 13 is a perspective view thereof; and,

FIG. 14 is a reference perspective view in use thereof.

The nail clipper has a nail file within and exposed through the top opening in the lever.

The portion of the nail clipper shown in broken lines forms no part of the claimed design.
